Inventor:

William T. Collins

UNITED STATES PATENT OFFICE.

WILLIAM T. COLLINS, OF WINCHESTER, ILLINOIS.

IMPROVEMENT IN CAR-COUPINGS.

Specification forming part of Letters Patent No. **135,890**, dated February 18, 1873.

To all whom it may concern:

Be it known that I, WILLIAM T. COLLINS, of Winchester, in the county of Scott and State of Illinois, have invented a new and Improved Attachment for Car-Couplings; and I do hereby declare that the following is a full, clear, and exact description thereof, reference being had to the accompanying drawing and the letters of reference marked thereon, which form a part of this specification.

Letter A of the drawing indicates a longitudinal vertical sectional view of my invention. Letter B indicates a top view. Letter C indicates a side view.

The mode of constructing my device is as follows: The slide *b* should be so fastened as to slide in openings *c* on each side of opening *d* of plate *a*, and extend above so far that in no event they will pass under the drop *e* of slide *f*, and extend below so far that in every event they will receive the end of the link *g* in the act of coupling the cars, and being driven to the back end of the openings *c* will thereby press back the slide *f*, so as to enable the pin *z* to so fall through the link and boxing as to couple the cars; and being arrested by the back end of openings *c*, the plate *a* yielding upward on pivots *y*, the slides *b* will jump the end and fall on the inside of the link *g*, ready, upon the withdrawal of the link, to repeat,

upon coupling the cars, the same operation. The office of the spring *k* is to throw the slide *f* back under the pin *z* upon the same being withdrawn or the cars being uncoupled. With slides *b*, constructed so as to operate as above, and attached, the plate *a* should be hung on pivots *y* in grooves *x* to the front of the pin-hole *h*, at a distance from the bottom of the device of about one-fourth less than the thickness of the link used, the pivots *y* yielding in grooves *x*, so as to accommodate the plate *a* to the thickness of the link. The spring *w* should be so constructed as to fall within itself, and be fastened to the top of the device around the pin-hole *h*, the widest end thereof resting and pressing upon plate *a*, so as to hold the link *g*, when coupled, in a horizontal position.

What I claim as my invention, and desire to secure by Letters Patent, is—

The combination, with a bunter having vertical grooves *x*, of the sliding catches *b*, the slide *f*, flange *e*, springs *k* and *w*, and the tilting-plate *a* pivoted in slot *y*, to have vertical as well as pivotal motions, substantially as specified.

WILLIAM T. COLLINS.
